UNITED STATES PATENT OFFICE.

EMIL FILLMANN, OF CHICAGO, ILLINOIS.

DESIGN FOR A MOLDING FOR A PICTURE-FRAME.

SPECIFICATION forming part of Design No. 14,375, dated October 30, 1883.

Application filed August 27, 1883. Term of patent 3½ years.

To all whom it may concern:

Be it known that I, EMIL FILLMANN, a citizen of the United States of America, residing at Chicago, in the county of Cook and State 5 of Illinois, have invented and produced a new and original Design for Moldings, of which the following is a specification, reference being had therein to the accompanying illustration.

- 10 The molding as illustrated in the print, which is a perspective of the same, consists of the base proper, a crown-mold, a scotia, a panel, and a bed-mold, each part of the shape and configuration described.
- 15 A represents the base of the molding, which is curved at its rear, as shown. B is the crown-mold, which is ornamented with a series of diamond-shaped frames, a, in the center of each of which is formed a stem with three 20 leaves, b. Below the crown-mold B is placed a strip, C, which divides said crown-mold from the scotia D. This scotia is ornamented with certain designs, which consist of a series of

Gothic arches, e, in front of each one of which is placed a representation of a bush, upon 25 which are a number of flowers and leaves, and at the lower extremity are placed a number of rosettes, each one of which is placed between two of the arches above referred to. At the point shown a narrow strip, E, is formed, said 30 strip dividing the scotia from a panel, F. This panel presents a flat upper surface, and at its outer edge is formed a curved strip, G, said strip dividing the panel from the bed-mold H.

What I claim is—

35 The design for a molding, consisting of a crown-mold, a scotia, a flat sanded panel, and a bed-mold, the several parts suitably ornamented and separated from each other by strips, as described and shown.

40 In testimony whereof I affix my signature in presence of two witnesses.

EMIL FILLMANN.
